UNITED STATES PATENT OFFICE.

CYRUS W. BALDWIN, OF YONKERS, NEW YORK, ASSIGNOR TO WILLIAM E. HALE, OF CHICAGO, ILLINOIS.

GOVERNOR.

SPECIFICATION forming part of Letters Patent No. 368,446, dated August 16, 1887.

Application filed April 27, 1887. Serial No. 236,344. (No model.)

To all whom it may concern:

Be it known that I, CYRUS W. BALDWIN, a citizen of the United States, residing at Yonkers, Westchester county, New York, have invented certain new and useful Improvements in Governors, of which the following is a specification.

The present invention relates to devices for governing or regulating the speed of engines, motors, or other devices; and it consists in a novel governor automatically operated by an engine or motor for controlling a throttle or induction valve, or other regulating device.

In the drawings, Figure 1 is a side elevation of so much of a gas-engine as will illustrate an application of the improved governor. Fig. 2 is a plan view thereof. Fig. 3 is an enlarged central vertical section of a portion of the engine-cylinder, a valve, and a regulator adapted to be controlled by the improved governor. Fig. 4 is an enlarged elevation of the governor. Fig. 5 is a central vertical section of the same, taken on the line d. Fig. 6 is a plan view of the end of the regulating-rod, and Fig. 7 is a sectional detail taken on the line e of Fig. 4.

In an application filed by me in the United States Patent Office August 19, 1886, No. 211,299, I have set forth and illustrated a speed-regulating device for engines, consisting of a pair of parallel disks driven by the engine, a third disk arranged between said parallel disks and connected so as to operate an engine-valve and a governor—a ball-governor, as shown—operating to cause one or the other of the parallel disks to be brought into frictional contact with said third disk, according as the speed of the engine increases or decreases.

It is sometimes desirable to employ with high-speed engines a more compact structure than the use of a ball-governor permits, and to employ a governor whose action is more sensitive.

As shown in said drawings, Figs. 1 and 2, A represents the bed of an engine—a gas-engine is illustrated—supporting at one end the cylinder B, at the other the pillow-blocks, in which turns the crank-shaft C, carrying a fly-wheel, 15, the crank being connected by a rod, 2, with the piston-rod, as is usual.

The improved governor G is contained by a flanged casting, 69, secured to the crank-shaft or carried by or secured to the fly-wheel 15. Within the flange 70 of this casting are pivoted at 71 71 two levers, 72 72, each carrying a heavy weight, 73, which tends to fly outward with the levers by centrifugal force when the fly-wheel rotates, and a strong spring, 74, connected to the outer end of each lever 60 and the opposite lever near the pivoted end thereof, tends to draw the levers inward, and a set-screw, 75, on each weight is set to limit, by abutting against said flange 70, the outward movement thereof.

Upon the shaft C turns a ring, K, having a peripheral groove, v, to receive swiveling-lugs 76 76, extending from opposite sides of a yoke, L, suspended from a rocking pin, 77, passing through a rock-rod, 78, supported by 70 one of the pillow-blocks 79. The ring K has slots w, (shown in dotted lines, Fig. 4, and in Fig. 7,) into which extends lugs 80 on the hub of the wheel or the casting 69, and the ends of the slots and lugs are beveled, so that a very 75 slight turning of the ring will bring the beveled faces together and thus cause the ring to move outward, carrying with it the yoke L. A spring, 81, Fig. 5, between the yoke and the pillow-block, forces the yoke and ring inward 80 to keep the beveled faces in contact as soon as the ring is turned. The turning of the ring is effected by the action of the weighted levers, which are connected by rods 82 with lugs on the ring.

The face of the recess v is eccentric to the shaft C, as shown by dotted lines, Fig. 4, so that the yoke L is vibrated with its supporting rocking rod 78 as the ring K is turned by the movement of the weighted levers, and the 90 lower end of the yoke terminates in a fork, the two prongs 83 84 of which project past and upon opposite sides of a rod, k. The end of this rod k is formed into steps or provided with shoulders u, receding in opposite directions, as best shown in Fig. 6.

When the parts are in the position shown in Fig. 4, the vibration of the yoke in the direction of the arrow 3 4 will have no effect on the rod k; but when on the outward or inward 100 motion of the weighted levers the ring K is turned and the yoke L is swung in the direc-

tion of the arrow 2, Fig. 5, the prong 83 will catch on one of the shoulders u , and as the yoke then swings in the direction of the arrow 3 it will carry with it the rod k , and if the 5 weighted levers continue to fly out the yoke will move farther in the direction of the arrow 2 and the prong 83 will catch on the next shoulder and feed the rod k farther backward. If, however, the weighted levers do not continue to move outward, the yoke will simply play back and forth until the levers swing inward, when the yoke will swing out in a direction the reverse of the arrow 2, and the prong 84 will engage with one of the shoulders u on the opposite side and the rod will be moved step by step back in the direction of the arrow 4 until the movement of the weighted levers is arrested or reversed. As an extremely slight movement of the levers will 15 turn the ring K , and as a very slight turning of the ring will shift the lateral position of the vibrating yoke, it is evident that a very slight increase or decrease in the speed of the engine will vary the position of the rod k , and of the 20 regulating appliances to which it is connected. The movements of the yoke L are thus made 25 through suitable connections—such as the rod k —for altering the position of the governing or controlling valve, shifting-bar, 30 electrical switch, or other engine-regulator, according to the character of the engine, or for throwing in and out resistances in an electric circuit, it being of course understood that the intermediate devices or connections with 35 such regulator may be varied to a great extent.

The regulator illustrated in the drawings consists of a wedge, H , slotted to pass the hub of a valve-casing between it and a nut, 29, upon the end of the spindle of a valve, G' , the 40 lift of which controls the flow of the gaseous mixture to the cylinder B of the engine, as is fully set forth in an application filed by me of even date herewith.

In the construction shown herein the regulator H is carried at one end of a pivoted lever, 64, carrying at the other end a pivoted bearing secured upon the end of the rod k , which latter is guided in suitable bearings, so as to be capable of a sliding movement imparted 50 thereto by the motion of the yoke L .

It is obvious that the flanged casting 69, supporting the improved governor, may be a belt or other pulley adapted to transmit the power of the engine or other source of power 55 to devices to be operated.

I do not claim herein the combination of the parts described with a gas-engine, as this will constitute the subject-matter of a separate application for Letters Patent.

60 What I claim is—

1. In a governor consisting of pivoted weighted levers carried by a revolving shaft and operated by centrifugal force, the combination, with said weighted levers, of a vibrating and laterally-moving yoke, cams operated 65 by the weighted levers for moving said yoke

laterally, and a rod adapted to be moved by the yoke, substantially as described.

2. The combination, with weighted levers supported and carried by a revolving shaft 70 and operated by centrifugal force, of a vibrating and laterally-moving yoke, cams operated by said levers for moving said yoke laterally, fingers projecting from the yoke, and a rod adapted to be engaged and moved by said fingers, substantially as described. 75

3. The combination, with weighted levers supported and carried by a revolving shaft 80 and operated by centrifugal force, of a vibrating and laterally-moving yoke, cams operated by said levers for moving said yoke laterally, and a stepped rod adapted to be engaged and moved by said yoke, substantially as described. 85

4. The combination, with weighted levers supported and carried by a revolving shaft 85 and operated by centrifugal force, of a vibrating and laterally-moving yoke, cams operated by said levers for moving said yoke laterally, fingers projecting from the yoke, and a stepped rod adapted to be engaged and moved by said 90 fingers, substantially as described.

5. The combination, with weighted levers supported and carried by a revolving shaft 95 and operated by centrifugal force, of a yoke, a ring interposed between said levers and the yoke and provided with cams for both vibrating and laterally moving said yoke, and a rod adapted to be moved by the yoke, substantially as described.

6. The combination, with weighted levers supported and carried by a revolving shaft 100 and operated by centrifugal force, of a yoke, a ring interposed between said levers and the yoke and provided with cams for both vibrating and laterally moving said yoke, fingers 105 projecting from the yoke, and a rod adapted to be moved by the fingers, substantially as described.

7. The combination, with weighted levers supported and carried by a revolving shaft 110 and operated by centrifugal force, of a yoke, a ring interposed between said levers and the yoke and provided with cams for both vibrating and laterally moving said yoke, fingers 115 projecting from the yoke, and a stepped rod adapted to be engaged and moved by the fingers, substantially as described.

8. The combination, with weighted levers supported and carried by a revolving shaft 120 and operated by centrifugal force, of a ring connected with said levers and provided with cams, a yoke vibrated and laterally moved by said cams, fingers projecting from the yoke, and a stepped rod adapted to be engaged and moved by the fingers, substantially as described. 125

9. The combination, with weighted levers supported and carried by a revolving shaft 130 and operated by centrifugal force, of a yoke pivotally mounted at one end and at the other provided with fingers adapted to engage with a rod, and cams operated by the levers for both

vibrating and laterally moving said pivoted yoke and moving said rod, substantially as described.

10. The combination, with weighted levers supported and carried by a revolving shaft operated by centrifugal force and retracted by springs, a ring surrounding said shaft and connected with said levers, a vibrating and laterally-moving pivoted yoke, cams carried by said ring for vibrating and laterally moving said yoke, fingers projecting from the

yoke, and a stepped rod adapted to be engaged and moved by said fingers, substantially as described.

In testimony whereof I have signed my name 15 to this specification in the presence of two subscribing witnesses.

CYRUS W. BALDWIN.
